COVER GRIP FOR IRONING BOARDS
AND THE LIKE

Mary C. Gresser, Los Angeles, Calif.

Application June 16, 1950, Serial No. 10,577

Term of patent 14 years

(Cl. D17—8)

To all whom it may concern:

Be it known that I, Mary C. Gresser, a citizen of the United States and a resident of the city of Los Angeles, in the county of Los Angeles and State of California, have invented a new, original, and ornamental Design for a Cover Grip for Ironing Boards and the Like, of which the following is a specification, reference being had to the accompanying drawing, forming part thereof, in which:

Fig. 1 is a perspective view of a cover grip for ironing boards and the like showing my new design;

Fig. 2 is an enlarged perspective view of an end portion thereof;

Fig. 3 is a view of the opposite side of the end portion of Fig. 2.

Fig. 4 is a side edge view of Fig. 3; and

Fig. 5 is an end view of Fig. 2.

I claim:

The ornamental design for a cover grip for ironing boards and the like, as shown.

MARY C. GRESSER.
